UNITED STATES PATENT OFFICE.

CARL MUEHLEISEN, OF BERLIN, GERMANY, ASSIGNOR TO MERGENTHALER LINOTYPE COMPANY, A CORPORATION OF NEW YORK.

MEANS FOR CONTROLLING THE PUMP OR THE INDENTER OF A MACHINE FOR MAKING PRINTING-SLUGS.

1,133,568.

Specification of Letters Patent. Patented Mar. 30, 1915.

Application filed November 11, 1914. Serial No. 871,450.

To all whom it may concern:

Be it known that I, CARL MUEHLEISEN, a citizen of the United States of America, residing at Chausseestrasse 23, Berlin, No. 4, 5 in the Empire of Germany, have invented new and useful Improved Means for Controlling the Pump or the Indenter of a Machine for Making Printing-Slugs, of which the following is a specification.

10 The present invention relates to improved means for enabling the condition in respect of justification of a typographical line composed in a machine for making printing slugs from such lines, to control the metal-injecting pump, or the flong-indenting device thereof, whichever that machine may be equipped with.

There are known at the present time two types of machine for making printing slugs 20 from composed lines. One of these composes matrices and spaces into a line; places that line between two jaws fixed at a distance apart equal to the standard length of slug; operatively thickens each spacer till 25 the line is tight, *i. e.* justified; presses a mold for the body of the slug metal-tight against the row of character-forming cavities in the line, the junction of that mold with the said row forming a mold for the slug; and 30 makes a pump inject molten metal into the last mentioned mold till the latter is filled under pressure, thereby casting a printing slug. This type is known as the Mergenthaler and commercially under the trademark "Linotype." The other type substitutes type-dies for matrices; indents a flong 35 by pressing it and the line together, thereby producing a matrix; and casts from the latter in the way just described. Both types 40 are described in the specification of Letters Patent No. 436532 dated September 16th, 1890.

Experience with the machine of the first type showed that matrices would sometimes 45 jam in the guides which held them while the spacers were being thickened, with the result that the act of thickening failed to justify the line to the standard length, so that it was loose instead of tight when the pump 50 acted and the metal was squirted between the matrices and over the adjacent parts of the machine. Such accidents are now prevented by one of the jaws being movable outward up to the standard length and con-

nected to the pump in such a way that it 55 holds the pump locked until it has been so moved, when, the line being tight, the pump is unlocked and acts. In the case of a machine of the second type, a jammed matrix would prevent justification in exactly the 60 same way as in a machine of the first type, the mischievous result being a badly justified and therefore spoilt indented matrix instead of a squirt of metal.

From the point of view of the present invention, the pump of the first type and the indenter of the second type are the equivalents of each other, because they have the common function of making a counterpart of the characters in the composed line and 65 are the devices to be respectively unlocked, and the difference between a matrix and a type-die becomes immaterial, and either is referred to by the term "piece" in the subsequent part of this specification and the 70 75 claims.

The present invention consists in means by which the joint outward movements of both jaws is required to unlock the said device. As a result, if a matrix becomes jammed so 80 as to prevent the proper justification of the line, at one side or the other thereof, the casting or forming action cannot take place, and the objections which would otherwise obtain thereby avoided.

85 The accompanying figures illustrate two preferred constructional forms of the application of it to a machine of the first type.

In them Figure 1 is a plan showing the composed line justified in both directions 90 from the middle of it, both jaws movable and the pump unlocked by the two jaws acting together; Fig. 2, a detail front elevation of part of Fig. 1; and Fig. 3, a plan of another form.

95 Referring to Figs. 1 and 2, 1 is the metal pot; 2, the pump; 3, its operating lever; 4, the pieces and 5, the spacers of the composed line confined between 7 and 8, the two movable jaws; 9, the so-called vise-top to which the latter are connected to move outward and inward in the direction of the length of the said line; 10, an abutment on the lever 3; 11, a bell crank lever fulcrumed at 12 on the machine frame and normally held by a 100 spring 13 under the abutment 10 to lock the pump 2 out of action, and 14, a lever of the first class fulcrumed at 15 on the ma-

chine frame in front of the lever 11 and having its rear end pivotally connected by a slot and pin device 16 with the front arm of that lever as heretofore. In the known controlling arrangement, the outward motion of the jaw 8, makes it engage the front end of the lever 14 directly. According to the present invention, there is a two-armed lever 17 fulcrumed on a stud 18 standing up from the vise-top 9. Instead of a hole fitting the stud 18, this lever has a slot 19 alined with the direction in which the front end of the lever 14 must be moved to unlock the pump 2. This lever 17 engages with the front end of the lever 14 either directly or through an adjustable contact piece 22 carried by the said end. Further, there are a second two-arm lever 23, pivoted on a stud 24 likewise standing up from the vise-top 9, and a rod 25 sliding in a suitable guide 26 and having one end pivotally connected with the front arm of the lever 23 and the other in constant engagement with the front arm of the lever 17 and keeping the rear arms of both levers 17 and 23 in constant engagement with the respective jaws 8 and 7.

27 is the known justifier which acts as heretofore by using and pushing the spacers 5 upward through the line, thereby thickening them in the known way.

The action of the constructional form just described is as follows: If none of the pieces 4 jam in their guides, both jaws 7 and 8 are moved outward more or less equally as to distance, by the act of justification, and the two arms of the lever 17 are engaged simultaneously by the jaw 8 and the rod 25, and as the lever 17 has the slot 19 instead of a hole it is pushed as a whole in the proper direction and far enough to unlock the pump 2, its median point engaging the lever 14 for that purpose. If the piece exactly in the middle of the line is jammed, the action is as just described. If the position of the jammed matrix with reference to the jaws 7 and 8 is such that only one of the latter is moved outward, the lever 17 (the right end of the slot 19 being then up to the stud 18) is rocked on its stud 18 instead of being pushed in the way described above, both of its edges 20 and 21 being so shaped as not to actuate the lever 14 to such extent as to unlock the pump lever 3.

Referring to Fig. 3, the constructional form illustrated therein differs from the one just described in dispensing with the parts 17 to 26 and having a duplicate on the opposite side of the pump 2 and its lever 3, of each of the parts 10 to 16. To both distinguish and identify the duplicate parts, their references have the letter "a" added to them. The action of this form is as follows: If one of the pieces 4 jam in their guides, both jaws 7 and 8 are moved outward more or less equally as to distance,

by the act of justification, each jaw engaging the respective lever 14 and 14^a and rocking it far enough to unlock the pump 2 by removing the bell crank levers 11, 11^a, from under the respective abutments 10, 10^a. If the piece 4 exactly in the middle of the line is jammed, the action is as just described. If the position of the jammed piece with reference to the jaws 7 and 8 is such that only one of the latter is moved outward, the lever 11 or 11^a as the case may be, connected to the other of them is left under its abutment 10 or 10^a, it therefore holding the pump 2 locked.

Having described my invention, I declare that what I claim and desire to secure by Letters Patent is:—

1. In a machine for making printing slugs from a line of pieces confined between two jaws, the combination of two line-confining jaws independently operative, a normally locked device for making a counterpart of the characters in that line, and means dependent upon the conjoint operation of the two jaws to unlock the device. 90

2. In a machine for making printing slugs from a line of pieces confined between two jaws, the combination of a device for making a counterpart of the characters in that line, two line-confining jaws independently movable, and an independent connection from each jaw to the said device to control its operation. 95

3. In a typographical casting machine, the combination of a pump, a pair of line 100 confining jaws each mounted to yield under the expanding influence of the line, and means to prevent the action of the pump unless both jaws yield conjointly.

4. In a typographical casting machine, 105 the combination of a pump, locking means therefor, a pair of line confining jaws arranged to yield under the expanding influence of the line, and means dependent upon the conjoint yielding action of both jaws to unlock the pump. 110

5. In a typographical casting machine, the combination of a pump, two confining jaws, a composed line therebetween, and means for expanding the line, the two confining jaws being arranged to permit each of the opposite ends of the line to move outward during the expanding action, with means to prevent the action of the pump, unless both ends of the line are so moved, 120 for the purpose described. 115

6. In a typographical casting machine, the combination of a pump, two locking devices therefor, a pair of line confining jaws each arranged to move outward under the expanding influence of the line, and independent connections between the jaws and the two locking devices. 125

7. In a machine of the class described, the combination of two confining jaws, a 130

composed line located therebetween, and means for expanding the line, the two confining jaws being arranged to permit each of the opposite ends of the line to move outward during the expanding action, with a device for making a counterpart of the characters in the composed line, together with means to prevent the operation of said

device unless both ends of the line are moved outward during the expanding action. 10

In witness whereof I have hereunto set my hand in the presence of two witnesses.

CARL MUEHLEISEN.
